(57) **CLAIM**

The ornamental design for a tablet personal computer, as shown and described.

DESCRIPTION

FIG. 1 is a front perspective view of the tablet PC while in an opened position showing our new design;

FIG. 2 is a front view thereof;

FIG. 3 is a rear view thereof;

FIG. 4 is a right side view thereof;

FIG. 5 is a left side view thereof;

FIG. 6 is a cross-sectional view thereof taken along line 6—6 of FIG. 3;

FIG. 7 is a top plan view thereof;

FIG. 8 is a bottom plan view thereof;

FIG. 9 is a rear perspective view thereof;

FIG. 10 is a perspective view thereof while in a closed position; and,

FIG. 11 is a bottom perspective view thereof.
